(57) **CLAIM**

The ornamental design for a perfume bottle, as shown and described.

DESCRIPTION

FIG. 1 is a perspective view of a first embodiment of a perfume bottle, according to a new design;

FIG. 2 is a left side view thereof;

FIG. 3 is a right side view thereof;

FIG. 4 is a back view thereof;

FIG. 5 is a front view thereof;

FIG. 6 is a top view thereof; and

FIG. 7 is a bottom view thereof.

FIG. 8 is a perspective view of a second embodiment of a perfume bottle, according to a new design;

FIG. 9 is a left side view thereof;

FIG. 10 is a right side view thereof;

FIG. 11 is a back view thereof;

FIG. 12 is a front view thereof;

FIG. 13 is a top view thereof; and

FIG. 14 is a bottom view thereof.

FIG. 15 is a perspective view of a third embodiment of a perfume bottle, according to a new design;

FIG. 16 is a left side view thereof;

FIG. 17 is a right side view thereof;

FIG. 18 is a back view thereof;

FIG. 19 is a front view thereof;

FIG. 20 is a top view thereof; and,

FIG. 21 is a bottom view thereof.

The broken lines shown in the drawings illustrate portions of the perfume bottle form no part of the claimed design. The break lines shown in the middle portion of the perfume bottle in FIGS. 8-12, 15-17 and 20-21 indicate that the

(Continued)

appearance of any portion of the article between the break lines forms no part of the claimed design.
